(57) **CLAIM**

The ornamental design for personal care product with indicia,
as shown and described.

DESCRIPTION

FIG. 1 is a perspective front view of personal care product
with indicia showing my new design;

FIG. 2 is a front view of the personal care product with indicia
of FIG. 1;

FIG. 3 is a back view of the personal care product with indicia
of FIG. 1;

FIG. 4 is a side view of the personal care product with indicia
of FIG. 1; the right side and left side views of the personal care
product with indicia are the same.

FIG. 5 is a bottom view of the personal care product with
indicia of FIG. 1; and

FIG. 6 is a top view of the personal care product with indicia
of FIG. 1.

FIG. 7 is a perspective front view of the mirror image of the
personal care product with indicia of FIG. 1;

FIG. 8 is a front view of the mirror image of the personal care
product with indicia of FIG. 7;

FIG. 9 is a back view of the mirror image of the personal care
product with indicia of FIG. 7;

FIG. 10 is a side view of the mirror image of the personal care
product with indicia of FIG. 7; the right side and left side
views of the personal care product with indicia are the same;

FIG. 11 is a bottom view of the mirror image of the personal
care product with indicia of FIG. 7; and

FIG. 12 is a top view of the mirror image of the personal care
product with indicia of FIG. 7.

FIG. 13 is a perspective front view of another embodiment of
personal care product with indicia, embodying the new
design;

FIG. 14 is a front view of the personal care product with
indicia of FIG. 13;

FIG. 15 is a back view of the personal care product with
indicia of FIG. 13;

FIG. 16 is a side view of the personal care product with indicia
of FIG. 13; the right side and left side views of the personal
care product with indicia are the same;

FIG. 17 is a bottom view of the personal care product with
indicia of FIG. 13; and

FIG. 18 is a top view of the personal care product with indicia
of FIG. 13.

FIG. 19 is a perspective front view of the mirror image of the
personal care product with indicia of FIG. 13;

FIG. 20 is a front view of the mirror image of the personal care
product with indicia of FIG. 19;

FIG. 21 is a back view of the mirror image of the personal care
product with indicia of FIG. 19;

FIG. 22 is a side view of the mirror image of the personal care
product with indicia of FIG. 19; the right side and left side
views of the personal care product with indicia are the same;

FIG. 23 is a bottom view of the mirror image of the personal care product with indicia of FIG. 19; and
FIG. 24 is a top view of the mirror image of the personal care product with indicia of FIG. 19.
FIG. 25 is a perspective front view of another embodiment of personal care product with indicia, embodying the new design;
FIG. 26 is a front view of the personal care product with indicia of FIG. 25;
FIG. 27 is a back view of the personal care product with indicia of FIG. 25;
FIG. 28 is a side view of the personal care product with indicia of FIG. 25; the right side and left side views of the personal care product with indicia are the same;
FIG. 29 is a bottom view of the personal care product with indicia of FIG. 25; and
FIG. 30 is a top view of the personal care product with indicia of FIG. 25.
FIG. 31 is a perspective front view of the mirror image of the personal care product with indicia of FIG. 25;
FIG. 32 is a front view of the mirror image of the personal care product with indicia of FIG. 31;
FIG. 33 is a back view of the mirror image of the personal care product with indicia of FIG. 31;
FIG. 34 is a side view of the mirror image of the personal care product with indicia of FIG. 31; the right side and left side views of the personal care product with indicia are the same;
FIG. 35 is a bottom view of the mirror image of the personal care product with indicia of FIG. 31; and
FIG. 36 is a top view of the mirror image of the personal care product with indicia of FIG. 31.
FIG. 37 is a perspective front view of another embodiment of personal care product with indicia, embodying the new design;

FIG. 38 is a front view of the personal care product with indicia of FIG. 37;
FIG. 39 is a back view of the personal care product with indicia of FIG. 37;
FIG. 40 is a right side view of the personal care product with indicia of FIG. 37;
FIG. 41 is a left side view of the personal care product with indicia of FIG. 37;
FIG. 42 is a top view of the personal care product with indicia of FIG. 37; and
FIG. 43 is a bottom view of the personal care product with indicia of FIG. 37.
FIG. 44 is a perspective front view of the mirror image of the personal care product with indicia of FIG. 37;
FIG. 45 is a front view of the mirror image of the personal care product with indicia of FIG. 44;
FIG. 46 is a back view of the mirror image of the personal care product with indicia of FIG. 44;
FIG. 47 is a right side view of the mirror image of the personal care product with indicia of FIG. 44;
FIG. 48 is a left side view of the mirror image of the personal care product with indicia of FIG. 44;
FIG. 49 is a bottom view of the mirror image of the personal care product with indicia of FIG. 44; and,
FIG. 50 is a top view of the mirror image of the personal care product with indicia of FIG. 44.
Broken lines shown in the figures described above are for illustrative purposes only and form no part of the claimed design. FIGS. 1-50 are lined for contrasting colors in accordance with MPEP § 608.02.
